UNITED STATES PATENT OFFICE.

ERNEST ROWLAND HILL, OF EAST ORANGE, NEW JERSEY, ASSIGNOR TO THE WESTINGHOUSE AIR BRAKE COMPANY, OF PITTSBURGH, PENNSYLVANIA, A CORPORATION OF PENNSYLVANIA.

AUTOMATIC TRAIN-CONTROLLING SYSTEM.

1,168,499.

Specification of Letters Patent. Patented Jan. 18, 1916.

Application filed March 11, 1910. Serial No. 548,525.

To all whom it may concern:

Be it known that I, ERNEST ROWLAND HILL, a citizen of the United States, residing at East Orange, county of Essex, and 5 State of New Jersey, have invented certain new and useful Improvements in Automatic Train-Controlling Systems, of which the following is a full, clear, and exact description.

This invention relates to automatic train stops for bringing a car or train to a stop, or reducing the speed thereof upon running past a signal set at danger, and more particularly to that type of these devices in which a car or vehicle of the train is provided with 10 a depending arm or lever operatively connected with the train control system, such as the automatic air brakes, and adapted to cooperate with a trip device located along the track and connected with the signal system, whereby the controlling arm or lever 15 may be automatically actuated by the track trip device to cause an application of the brakes upon the train.

The principal object of my invention is to 20 provide an improved device of this character, which shall be of a simple and durable construction, capable of certain and positive operation, and having means for protecting the depending controlling member from 25 snow, ice, or other obstructions along the track, which might otherwise interfere with its proper operation, and cause many undesired applications of the brakes, resulting in 30 great inconvenience and serious delay in the movement of trains.

It will be apparent to those skilled in the art that the scheme thus briefly outlined can be embodied in a great variety of forms. The devices which I prefer to employ for 35 the purpose are illustrated in the accompanying drawings, in which—

Figure 1 is a side view of the complete apparatus. Fig. 2 is a section on line 2—2 of Fig. 1. Fig. 3 is a diagrammatic view 40 showing the trip-device in normal or inoperative position, and Fig. 4 is a similar view showing the trip-device raised and about to be engaged by the valve-guard or plow on the train. Fig. 5 is a side view showing a 45 modification of the preferred embodiment of the invention.

The valve 3, connected to the train-pipe of the air-brake system of the train through a suitable part 4, is carried by a frame 5

mounted on a convenient part of the car-truck, diagrammatically indicated at 6. The two arms 7 of this frame have their faces ribbed or corrugated to conform to correspondingly ribbed plates 8 on the truck, and are held in firm engagement with said plates 60 by bolts 9, passing through vertical slots 10 in said arms, to permit vertical adjustment of the frame, as will be readily understood.

The valve-lever or arm 11, by which the valve is operated, extends downwardly toward the track, indicated at 12, and pivoted to the frame 6 by their upper ends, in front and rear of the valve, are two guards or plows 13, 14, also extending downwardly toward the track. It will be noted that these 70 guards are free to swing outwardly from the valve-lever but that the supporting frame itself serves as a stop to prevent movement of the guards inwardly toward the valve-lever.

Below the track is a transverse shaft 15, actuated by or under the control of the signaling system through the instrumentality of any convenient and suitable means, not shown, and mounted rigidly on the shaft is 80 an arm 16. Pivoted on the end of the arm is a trip-member 17 comprising two angularly-spaced arms 18, 19, and an intermediate longer arm 20, provided with a cam head 21. The trip-member is normally held with the 85 setting arm 20 in alinement with the carrying arm 16 by means of a spring 22, the ends of which abut against two stops 23, 24 on the carrying arm, and two stops 25, 26 on the trip member. Pivotal movement of the trip-member is thus permitted by the yielding of the spring; but such movement is limited by two lugs 27, 28, arranged to engage an arc-shaped stop 29 on the arm 16, as will be 90 readily understood.

The position of the trip-device when the signal ahead is "clear" is below the path of the guard members 13, 14, as shown in Fig. 3, but when the signal changes, say to "danger" the trip device is raised to its vertical position, in which the cam head of the setting arm 20 extends into the path of the guard or plow 13, as shown in Fig. 4. The guard, incapable of rearward movement, therefore advances the setting arm, turning the trip-member on its pivot and bring the arm 19 up behind the guard and into the path of the valve lever 11, as shown in Fig. 1; the flat

bottom of the guard, against which the head 21 bears, preventing return movement of the trip member under the influence of its spring 22. The valve-lever 11 now engages the actuating arm 19, which can yield slightly, thus cushioning the blow, until the stops 28 and 29 come into engagement. The valve lever, thus actuated, opens the valve, whereupon the air escapes from the train pipe and the brakes are applied. As the train moves on the trip member is returned to its vertical position by the spring 22, leaving the setting arm 20 in the path of the rear guard or plow 14, which latter, however, swings to the rear and hence clears the arm. The entire trip device now remains in its raised position until the signal changes back to "clear"; whereupon the device is depressed again to the position of Fig. 3.

When the train is moving in the opposite direction or the car is reversed the guard 14 actuates the arm 20 to set the trip device, and the arm 18 operates the valve, as will be readily seen.

It will be noted that the top of the arms 18, 19, 20 are considerably wider than the guards 13, 14, and the valve lever 11. This makes it easier to properly locate the apparatus, avoiding the necessity of such extreme care in arranging the parts to insure their being in the same vertical plane.

In the modification shown in Fig. 5 the trip-device has a single arm 30, which is engaged and advanced by the guard or plow 13^a until cleared by the latter, after which the trip-arm is restored to vertical position by its spring. In this construction the guard is located sufficiently in advance of the valve-lever to give enough time for the trip-arm to rise before its position is reached by the valve-lever when the train is running at full speed. It will be understood, of course, that the trip-arm spring is sufficiently powerful to insure operation of the valve. The other guard member, 14^a, becomes effective when the train is running in the opposite direction or the car reversed.

In both constructions the guard member or plow which happens to be in front, with reference to the movement of the train, effectually clears snow and other obstructions from the path of the valve-lever, but does not prevent or interfere with the function of the trip-device.

As previously stated, I prefer the devices herein described, but it is to be understood that the invention is capable of embodiment in other forms without departure from its proper spirit and scope.

I claim:

1. In an automatic train control system, the combination of a train controlling member carried by the train, guards also carried by the train in front and in rear of said member to clear obstructions from its path,

and a track trip device provided with a movably mounted member having an arm adapted to be deflected by one of the guards, and another arm actuated by the movement of the first arm, for engaging the train controlling member. 70

2. In an automatic train control system, the combination of a train controlling member carried by the train, guards also carried by the train in front and rear of said member to clear obstructions from its path, and a pivotally mounted trip device adjacent to the track, and provided with an arm adapted to be projected into the path of one of said guards for actuation thereby, and also having means adapted to be projected into the path of said train controlling member by the movement of said arm. 75

3. In an automatic train control system, the combination of a train controlling member carried by the train, guards pivotally mounted in front and rear of said member, whereby one guard or the other serves to clear obstructions from the path of said member, according to the direction of travel of the train, and a track trip device provided with a movably mounted member having an arm adapted to be deflected by one of the guards, and another arm actuated by the movement of the first arm for engaging the train controlling member. 80

4. In an automatic train-control system, in combination, a train-controlling member carried by the train, guards pivoted in front and rear of said member, and incapable of movement toward the latter, a setting arm adjacent to the track and adapted to be projected into the path of the guards for actuation by one or the other thereof according to the direction of the train's travel, and a pair of arms operatively connected with said setting-arm in front and rear thereof whereby one or the other, according to the direction of the train's travel, will be projected into the path of the train-controlling member by the actuation of the setting arm. 100

5. In an automatic train control system, the combination with a train-controlling member carried by the train, and guards also carried by the train in front and rear of said member to clear obstructions from the path of said member, of a track trip-device having a movably mounted member adapted to be deflected by the guard and operate the train controlling member, and a yielding means for returning said member to normal position. 110

6. In an automatic train control system, the combination with a train controlling member carried by the train, and a guard carried by the train for clearing obstructions from the path of said member, said guard being movably mounted to be deflected in one direction, of a track trip device having a movably mounted member 125

adapted to be deflected by the guard and engage the train controlling member.

7. In an automatic train control system, the combination of a shaft, a carrying arm mounted on said shaft, a trip device pivotally mounted on said carrying arm and comprising a setting arm, a trip arm in line with and rigidly connected to the setting arm, the outer end of the setting arm in its 10 normal position being higher than the trip

arm, and a yielding spring mechanism permitting pivotal movement of said setting and trip arms, and operating to return the same to their initial positions.

In testimony whereof I affix my signature 15 in the presence of two subscribing witnesses.

ERNEST ROWLAND HILL.
